US00D669618S

(12) **United States Design Patent**
Ormsbee et al.(10) **Patent No.:** **US D669,618 S**
(45) **Date of Patent:** **** Oct. 23, 2012**(54) **FLEXIBLE LIGHTING DEVICE**(75) Inventors: **Bowden Ormsbee**, Longmont, CO (US);
Richard N. Case, Boulder, CO (US)(73) Assignee: **Nite Ize, Inc.**, Boulder, CO (US)(**) Term: **14 Years**(21) Appl. No.: **29/408,158**(22) Filed: **Dec. 7, 2011**
